UNITED STATES PATENT OFFICE.

WILLIAM H. MCFADDEN, OF PITTSBURG, PENNSYLVANIA, ASSIGNOR OF TWO-THIRDS TO JAMES HEMPHILL, OF SAME PLACE, AND JAMES F. TRACEY, OF SHERIDANVILLE, PENNSYLVANIA.

STOPPER FOR LADLES.

SPECIFICATION forming part of Letters Patent No. 668,450, dated February 19, 1901.

Application filed August 31, 1900. Serial No. 28,698. (No model.)

To all whom it may concern:

Be it known that I, WILLIAM H. MCFADDEN, a citizen of the United States, residing at Pittsburg, in the county of Allegheny and State of Pennsylvania, have invented or discovered certain new and useful Improvements in Stoppers for Ladles, of which improvement the following is a specification.

The invention described herein relates to certain improvements in mechanism for operating ladle-stoppers.

It is customary in the art to connect the ladle-stopper, which consists of a rod having a refractory covering and end piece, rigidly to a slide, which in turn is mounted with the freedom of vertical movement upon the outer side of the ladle. By reason of this rigid movement great care must be exercised in adjusting the stopper-rod, so that the end of the stopper will fit evenly and correctly in the discharge-opening of the bottom of the ladle. Although such adjustment can be effected when the stopper is first applied to the ladle or when the latter is relined, the stopper is apt to become twisted somewhat by the heat of the molten metal, so that in subsequent use the stopper will not bear evenly and tightly on its seat in the discharge-opening of the ladle, and when such is the case there will be a constant dripping of the metal from the ladle.

The present invention has for its object a construction of stopper-rod or its operating mechanism whereby the stopper is truly centered in line with the discharge-opening by the molten metal as it flows out and can accommodate itself to any irregularities of the seat of the stopper around the discharge-opening.

The invention is hereinafter more fully described and claimed.

In the accompanying drawings, forming a part of this specification, Figure 1 is a view, partly in section and partly in elevation, of a ladle having my improvement applied thereto. Figs. 2 and 3 are views in section and elevation, respectively, illustrating the manner of connecting the stopper-rod to its operating mechanism. Fig. 4 is an under side plan view of such connection. Figs. 5 and 6 are sectional elevations on an enlarged scale, illustrating different forms or modifications of connections between the stopper-rod and

the operating mechanism. Fig. 7 is a sectional elevation of a further modification of the stopper-rod connection. Fig. 8 is a side elevation of the same. Fig. 9 is a sectional plan of the construction shown in Fig. 7, the plane of section being indicated by the line IX IX, Fig. 7. Figs. 10 and 11 show, respectively, a sectional elevation and a sectional plan view of a further modification of the stopper-rod connection. Fig. 12 is a sectional elevation showing another modification. Figs. 13 and 14 are sectional elevations illustrating the application of my improvement to the stopper-operating mechanism.

In the practice of my invention the ladle 1 is constructed in the usual or any suitable manner and is provided with an outlet 2 through the bottom, preferably located near one side of the ladle.

The stopper, consisting of the rod 3, the end piece 4, and the protecting-sleeve 5, is constructed in the usual or any suitable manner. This rod is connected at its upper end by a loose joint (several forms of which are shown in the drawings) to an arm 6, which in turn is secured to post or standard 7^a, carried by the slide. This slide is mounted in suitable bearings formed on the plate 8, secured to the side ladle. This slide is adapted to be raised and lowered by means of a lever 9, pivotally mounted on the plate 8 and having one end connected to the slide 7. Suitable means are provided whereby the slide may be held in its different positions—such, for example, as that shown, consisting of wheel-nut 10, screwing onto a bolt 11, which passes through a slot in the slide 7 and is screwed to the plate 8.

One form of flexible connection between the stopper-rod and its shifting mechanism is clearly shown in Figs. 2, 3, and 4 and consists of a threaded rod 12, which passes through a slot in the arm 6 and is held in position by means of nuts 13. This rod is provided at its lower end with a spherical head or ball 14, which is clamped between two plates 15 and 16, provided with concave seats in their adjacent faces and held together by means of bolts 17. The plate 16 is provided with a yoke 18, to which is firmly secured the upper end of the stopper-rod 3. This construction permits of a swinging movement of the rod 3 in any direction independent of the rod-operat-

ing mechanism. In practice it is preferred to limit the swinging movement of the stopper-rod, so that its lower end will always be in such position relative to the conical seat formed at the inner end of the discharge-opening 2 that when pressed down the stopper will be guided by the inclined walls of the seat to a central position thereon. A convenient means for limiting the swinging movement of the stopper-rod consists in securing a plate or disk 19 on the rod 12, the disk being held by means of the nut 20 in such position relative to the plate 15 as to limit the swinging movements thereof. As the stopper-rod is of considerable length, a comparatively small movement of the clamping-plates 15 and 16 on the spherical head will permit of a considerable movement of the lower end of the stopper-rod.

In the construction shown in Fig. 5 a spherical head or ball 14^a is formed on the end of the arm 6^a of the operating mechanism, and around this head are clamped plates 15^a and 16^a, having their inner walls concave to fit the spherical head. Through the plates and spherical head is formed an opening for the passage of the stopper-rod 3, which is held in position by means of nuts 22, bearing against plates 15^a and 16^a, as shown. The hole or opening through the spherical head is enlarged or tapered from the center of such head, so as to permit of the oscillation of the rod 3 therein. The movement of the rod is limited, preferably, by means of an extension 24 on the end of the rod passing into an enlarged opening formed in the bracket 25 and bolted to the arm 6^a.

In the construction shown in Fig. 6 the arm 6^b is formed with a head or enlargement 14^b, having spherical seats, preferably concave, formed in its upper and lower ends. Disks 26 and 26^a, having spherical faces, are arranged at the opposite ends of the head 14^b, and through these disks and the head 14^b are formed openings for the passage of the stopper-rod 3, which is supported by the disk 26 through the medium of a nut 27, screwing onto the rod. The oscillating movement of the stopper-rod is limited by the disk 26^a, which is held in suitable relation to the lower end of the head 14^b by the nut 27^a.

In Figs. 7, 8, and 9 is shown a further modification or form of connection which consists of a disk or plate 28, provided on its upper surface with the yoke 29, to which is secured a threaded rod 12^a, adjustably attached to the arm 6 by means of nuts 13. A second plate 28^a is provided with a yoke 29^a, to which is secured the stopper-rod 3. The plate 28 is provided on its under side with lugs 30, and the plate 28^a is provided on its upper side with lugs 30^a. These plates are so arranged that a line passing through the lugs on one plate will be at right angles to a line passing through the lugs on the other plate. To each of these lugs 30 and 30^a are secured pins 31, which project outwardly between the two sections of ring 32. These sections are

provided in their adjacent faces with suitable seats for the reception of the ends of these pins 31, and the rings are secured together by means of screws 33, which can be inserted through suitable holes in the plate 28, as shown in Figs. 7 and 8. This construction is substantially similar to the gimbal-joint.

In Figs. 10 and 11 the flexible connection between the stopper-rod and the arm 6 is formed by two interlocking links 34 34^a, one of said links being provided with a threaded stem 35, whereby it may be secured to the arm 6, and the other link with a yoke 36, to which is connected the stopper-rod 3. As clearly shown in said figures, these links are so constructed as to have a limited movement on each other.

In Fig. 12 the stopper-rod 3 is provided at its upper end with a spherical head or ball 37, which is held in its seat 38, formed on the under side of the arm 6^b, by means of a plate 39, provided with a spherical seat and bolted to the arm 6.

In the construction shown in Fig. 13 the outer end of the arm 6^c has one of the clamping-plates 16^b formed integral therewith and the rod 3, passing through the ball or head 14^c, which is provided with projections 40, extending through the clamping-plates 16^b and 15^b. The projections and the holes through the plates 15^b and 16^b are so proportioned as to permit a small vibration of the ball and stopper-rod.

As shown in Fig. 14, the arm 6 may be formed on or rigidly secured to the stopper-rod 3, and the flexible joint or connection may be interposed between the arm 6 and the post or standard 7^a, carried by the slide 7. Any one of the constructions hereinbefore described may be employed for this purpose—as, for example, the flexible or universal joint shown in Fig. 14 is similar to the construction shown in Figs. 1 to 4, inclusive, but in reversed position.

It is characteristic of my improvement that as the molten metal will flow equally from all sides through the outlet when the stopper is raised the latter will be held centrally above said opening or outlet by the metal pressing against it from all sides and will maintain the stopper in such position until the flow of metal is cut off. It is also characteristic of my improvement that in case the stopper or stopper-seat are irregular the stopper-rod will have sufficient movement to permit the stopper to seat itself.

I claim herein as my invention—

1. The combination of a ladle having a discharge-opening in its bottom, a rod provided with a stopper at its lower end, mechanism for raising and lowering the stopper-rod, and a flexible connection permitting the stopper to swing in all directions interposed between the stopper-rod and its operating mechanism, substantially as set forth.

2. The combination of a ladle having a dis-

charge-opening in its bottom, a rod provided with a stopper at its lower end, mechanism for raising and lowering the stopper-rod, a universal joint interposed in the connection 5 between the stopper-rod and its operating mechanism, and means for limiting the swinging movement of the stopper-rod, substantially as set forth.

3. The combination of a ladle having a discharge-opening in its bottom, a rod provided with a stopper at its lower end, a slide mounted on the side of the ladle, an arm connected to said slide and a universal joint connected to said arm and to the stopper-rod, substantially 15 as set forth.

4. A ladle-stopper mechanism having in combination a rod provided with a stopper at its lower end, a carrying-arm, a head or enlargement connected to one of said parts, 20 clamping-plates secured to the other part, the bearing-faces of the head and the clamping-plates being curved and so arranged as to permit of a swinging of the stopper in all directions, and means for raising and lowering 25 said arm, substantially as set forth.

5. A ladle-stopper mechanism having in combination an arm having a head or enlarge-

ment provided at its upper end with a curved seat, a plate or disk having a correspondingly-curved face, a rod provided at its lower end with a stopper and extending loosely through the head and connected to the disk or plate, whereby the stopper-rod is permitted to swing in all directions, and means for raising and lowering the arm, substantially as set forth. 30

6. A ladle-stopper mechanism having in combination an arm having a head or enlargement provided at its ends with curved seats, plates or disks having correspondingly-curved faces arranged at opposite ends of the 40 head, a rod provided with a stopper at its lower end and extending loosely through the head and connected to the upper disk and means on the rod for holding the lower disk in proper relation to the head, and means for 45 raising and lowering the arm, substantially as set forth.

In testimony whereof I have hereunto set my hand.

WILLIAM H. McFADDEN.
